DESIGN FOR A GAME BOARD

Albert S. Moorman, Kew Gardens, N. Y.

Application August 8, 1946, Serial No. 132,350

Term of patent 7 years

(Cl. D34—5)

To all whom it may concern:

Be it known that I, Albert S. Moorman, a citizen of the United States, residing at Kew Gardens, in the county of Queens and State of New York, have invented a new, original, and ornamental Design for a Game Board, of which the following is a specification, reference being had to the accompanying drawing, forming part thereof.

Fig. 1 is a plan view of the game board constituting my new design;

Fig. 2 is an edge elevation of the same.

Fig. 3 is a fragmentary, enlarged, top perspective view of one of the stations constituting part of the design.

The dominant features of my design are shown in solid lines in the drawing.

I claim:

The ornamental design for a game board, substantially as shown and described.

ALBERT S. MOORMAN.
